UNITED STATES PATENT OFFICE.

JOHN V. LA GRANGE, OF CAIRO, ILLINOIS.

INKSTAND.

SPECIFICATION forming part of Letters Patent No. 695,402, dated March 11, 1902.

Application filed June 26, 1901. Serial No. 66,150. (No model.)

To all whom it may concern:

Be it known that I, JOHN V. LA GRANGE, a citizen of the United States, residing at Cairo, in the county of Alexander and State of Illinois, have invented new and useful Improvements in Inkstands, of which the following is a specification.

My invention relates to inkstands; and its object is to provide a sliding lid or cover for an ink-well which is adapted to be moved backward by a slight touch of the finger while the pen is held in writing position to uncover the ink-well and automatically retracted to cover the well when relieved of pressure, thus preventing undue evaporation of the ink and protecting it from dust and the deteriorating action of the air.

The invention comprises a casing, a tilting frame pivotally supported therein, a sliding cover and means for moving the cover rearward when the frame is tilted and for retracting the cover when pressure upon the frame is relieved.

The construction of the improvement will be fully described hereinafter in connection with the accompanying drawings, which form a part of this specification, and its novel features will be defined in the appended claims.

In the drawings, Figure 1 is a view in perspective of the preferred construction of the inkstand. Fig. 2 is a central vertical section of the same. Fig. 3 is a horizontal section on the line *x-x* of Fig. 2, showing the under side of the top portion of the device. Fig. 4 is a detail perspective view of the casing shown in Fig. 1. Fig. 5 is a bottom plan view of the preferred form of top. Fig. 6 is a perspective view of the preferred form of tilting frame. Fig. 7 is a view in perspective of the sliding cover. Fig. 8 is a similar view of the ink-well. Fig. 9 is a perspective view of one of the pivot-screws employed, and Fig. 10 is a similar view of one of the springs for retracting the cover.

The support or casing comprises a base 1, which is recessed, as at 2, to adapt it to receive an ink-well 3, parallel sides 4, and a back 5. Within this supporting-casing is arranged a frame comprising a top 6, depending parallel arms 7, and a cross-bar 8, the latter serving as the trip-bar to receive the pressure of the finger, as will be further ex-

plained hereinafter. The top 6 of the tilting frame is formed with an opening 9 to permit access to the ink-well arranged below it and with slots or openings 10 and 11 for the purpose hereinafter set forth.

The tilting frame is pivotally secured between the sides of the casing by screw-pivots 12, which are preferably of the form shown in Fig. 9 and pass through openings 13 in the sides 4 and registering openings 14 in the lower ends of the arms 7 of the frame.

15 designates a flat spring secured at its lower end to the back 5 of the casing, centrally of the width of the latter, and having its upper free end projected through the slot 11 in the top of the tilting frame to retract said frame after it is depressed.

16 designates the top of the casing, formed with a circular opening 17, adapted to register with the mouth of the ink-well, and with a recess 18, within which is supported a sliding cover 19. The sides of the top 16 are also recessed, as shown at 20, to adapt it to fit upon the sides 4 of the casing, to which it is removably secured by suitable fastening devices.

The under surface of the top 16 is formed with transverse recesses 21, within each of which is pivotally secured a lever 22 by means of pivots 23. The inner ends of these levers overlap and extend within a horizontal slot 24 of the cover 19 and are longitudinally slotted to engage a pin 25, extending through the cover 19. From the under side of each of the levers 22, at the outer ends thereof, depends a pin 26, said pins projecting into the slots 10 of the tilting frame, and each of said levers 22 is provided with a retracting-spring 27, said springs being secured at their forward ends in slits 28, formed on the under side of the top 16, while their rear ends bear against the outer ends of the levers, as best shown in Fig. 5.

The operation of the mechanism is as follows: Normally the sliding cover 19 is held in its forward position below the opening 17 of the top by the tension of the springs 27 upon the outer ends of the levers 22. When the pivoted frame is tilted forward by a slight pressure upon the trip-bar 8, the inner ends of the levers 22 are thrown rearward through the medium of the pins 26, which project into the slots 10 of the frame, and such rearward move-

ment of the slotted ends of said levers moves the cover 19 backward, thus uncovering the mouth of the ink-well. As soon as the trip-bar 8 is released the springs 27, which are compressed by the movement of the levers, return the levers and cover to their normal position, as will be apparent.

To hold the cover 19 in its rear position, I may employ a catch device comprising an angle-lever 29, fulcrumed on the under side of the top and having at one end a depending pin 30 and at its opposite end a hook 31. A spring 32, secured to the back 5 of the casing, bears against the pin 30, causing the hook 31 to engage the front edge of the cover when the latter is forced back. The catch-lever is operated to release the cover by the contact of the point 33 of the frame with the pin 30. This catch device avoids the tendency of the cover to move forward with every variation of pressure on the trip-bar.

Various changes in the details of the device may be resorted to without departing from the invention, and I would therefore have it understood that I reserve the right to make all such modifications and variations as may fall within the scope of the following claims.

I claim—

1. An inkstand comprising a casing adapted to support an ink-well, a tilting frame pivotally secured within said casing provided with a trip-bar, and formed with a central slot and side slots, a top recessed on its under side, a sliding cover below the top, a pair of horizontally-disposed levers fulcrumed on the under side of the top having pins on their

outer ends entering the side slots of the frame and connected at their inner ends with the cover, retracting-springs for said levers, and a retracting-spring for the frame extending 40 into the central slot of said frame.

2. An inkstand comprising a casing adapted to support an ink-well, a tilting frame pivotally secured within said casing and formed with side slots, a trip-bar on said frame, a 45 top recessed on its under side, a sliding cover guided below the top and having a horizontal slot and a pin, and a pair of horizontally-disposed levers fulcrumed on the under side of the top, slotted at their inner ends to engage the pin on the cover, pins depending from the outer ends of the levers and projecting into the side slots of the frame, and retracting-springs for said frame and levers.

3. The combination with a casing; of a tilting frame pivotally secured thereto and formed with slots; a trip-bar secured to said frame; a top fitting said casing; levers fulcrumed upon the under side of said top and provided with pins projecting into the slots 60 of the frame; a retracting-spring for said frame; a cover supported below said top and formed with a horizontal slot to receive the inner ends of the levers, a pin carried by the cover engaging the levers; and a catch device for said cover.

In testimony whereof I affix my signature in presence of two witnesses.

JOHN V. LA GRANGE.
